UNITED STATES PATENT OFFICE.

CHARLES M. CROOK, OF CHICAGO, ILLINOIS.

TIMING APPARATUS.

Application filed October 2, 1919. Serial No. 327,980.

To all whom it may concern:

Be it known that I, CHARLES M. CROOK, a citizen of the United States, residing at Chicago, in the county of Cook and State 5 of Illinois, have invented new and useful Improvements in Timing Apparatus, of which the following is a full, clear, concise, and exact description, reference being had to the accompanying drawing, forming a part 10 of this specification.

My invention relates to improvements in timing-devices, and is particularly adaptable for use in connection with the control of the operating periods of processes of various 15 kinds, such, for instance, as vulcanizing processes of rubber goods of various character.

One of the objects of my invention is to provide a means which will provide in a 20 small, self-contained device a timing apparatus which at the expiration of predetermined periods will cause a signal to be given either visible or audible, that the predetermined time has elapsed, or, if desired, stop 25 the process or method; and, furthermore, to provide means which during the entire period will show the length of time remaining before the signal will be sounded.

A further object of my invention is to 30 provide an indicator which may be operated from any ordinary lamp socket.

For the purpose of disclosing my invention, I have shown one embodiment of the same in the accompanying drawings.

35 In said drawings—

Fig. 1 is a front elevation of the device embodying my invention;

Fig. 2 is a sectional view taken on the line 2—2 of Fig. 1;

40 Fig. 3 is a sectional view taken on the line 3—3 of Fig. 2;

Fig. 4 is a sectional view taken on the line 4—4 of Fig. 2;

Fig. 5 is a detail view of the switch tripping mechanism in tripped position;

45 Fig. 6 is a similar view showing said mechanism in non-tripped position;

Fig. 7 is a detail sectional view of the starting mechanism;

50 Fig. 8 is a detail view of the stopping mechanism;

Fig. 9 is an elevation of the mechanism illustrated in Fig. 8;

Fig. 10 is a sectional view of the switch;

Fig. 11 is a sectional view taken on the 55 line 11—11 of Fig. 2;

Fig. 12 is a detail view of the latch; and Figs. 13 and 14 are views showing the driving motor for the mechanism.

In the embodiment illustrated, I provide a 60 cylindrical casing, preferably formed of metal and having a bottom or base section 1, and a side tubular section 2 secured thereto and forming together the casing. A cover for the casing comprising an annular flanged 65 ring 3 secured to the top of the member 2 and a glass front 4 suitably secured in position on the ring is provided, which cover is secured in position in any suitable manner. This cover is tightly secured in position and 70 makes a dustproof joint, as at 5, as likewise does the cylinder 2 with the bottom portion 1, as at 6.

All of the operating parts of the indicator 75 are arranged within this casing. Mounted within the casing and supported and secured in position upon suitable posts 7 is a supporting plate 8. This plate serves as a support for the various operating parts of the mechanism. On the under side of this plate 80 is mounted the operating motor 9, which will be more fully described hereinafter, which motor is provided with a driving pinion 10. On the upper side of the plate 8 and journaled between the plate 8 and the plate 11 85 is a shaft 12. This shaft has loosely mounted thereon a hub 13, which carries an indicating disc 14, said disc having an indicating arrow 15 on its upper face. The shaft 13 carries an indicating hand 16, and the arrow 15 and hand 16 cooperate with a suitable face 17 on the top of the plate 11. The face 17 has suitable indicia thereon, and in the example illustrated the plate is divided into five-minute intervals with minute graduates between. 90 These numerals progress in a clockwise direction, while the indicating hand 16 is adapted to be driven in a contra-clockwise direction. The disc 14 and its indicating arrow is adapted to be manually rotated, and to this end on the hub 13 a gear wheel 18 95 is mounted. This gear wheel meshes with a pinion 19 mounted on the shaft 20 journaled between the upper and lower plates 11 and 8, and this shaft carries a gear wheel 21 100 adapted to mesh with an elongated pinion 22. The elongated pinion is mounted on a shaft 23 adapted to project through the ring

105

3 and has on its upper end an operating knurled nut 24. In order that the casing may be made dustproof, at the point where the shaft 23 passes through the top thereof I provide a bushing 25, the lower end of which has a reduced opening just sufficiently large to accommodate the shaft 23, and surrounding the shaft is a suitable felt washer or other packing 26. This washer is held in position by means of a coiled spring 27 resting upon the bottom of the bushing and having its other end bearing against the lower end of the nut 24 to serve to maintain the pinion 22 in a raised position and in a position where its teeth will engage a locking tooth 28 on the under side of the plate 11, so that the pinion 22 will be held against rotation. A nut 29 on the top of the bushing aids in securing the bushing in place. In order to rotate the pinion and thereby set the disc 14, it is necessary to first depress the knob 24 to disengage the teeth of the pinion 22 from the locking pin 28, after which the knob may be rotated in either direction and the disc 14 set accordingly.

On the shaft 12 is mounted a driving gear 30, which is adapted to mesh with a pinion 31 mounted on the shaft 32, which shaft is mounted between the plates 33 forming a movable frame pivoted on the hollow studs 34 to the plates 8 and 11. A driving shaft 35 extends through the studs 34, so that the pivotal point of the frame will be concentric with this driving shaft. This driving shaft is provided with a pinion 36, which, in turn, meshes with a gear 37 on the shaft 32, so that the rotation of the gear 37 will transmit motion to the pinion 30. The lower end of the shaft 35 is provided with a gear 38, which, in turn, meshes with the driving pinion 10 of the motor. It will thus be seen that through the gearing carried on the movable frame formed by the plates 33 the motor is connected with and can drive the shaft 12. At the same time, due to the fact that the frame is pivoted, this frame can be swung so that the pinion 31 may be swung out of engagement with the gear 30, thereby disconnecting the motor from the shaft 12 without affecting in any way the running of the motor; in other words, the motor is adapted to be continuously operated, while the shaft 12 is adapted to be connected or disconnected therewith as occasion demands. The upper plate 33 has mounted thereon a dog 39 pivoted at 40 to the upper plate. The rear end of this dog is adapted, when the frame is moved outwardly to disconnect the pinion 30 from the gear 29, to engage in a notch 41 formed in the lower end of a vertically movable catch 42. This catch comprises a vertically movable rod having the longitudinal notch 42 formed in its lower end, into which the end of the dog

39 may engage, and just above the notch 42 a transverse notch 43, which, when the latch or rod is depressed, will free the dog. This rod is secured in position in the same manner as the shaft 23 and is prevented from turning by a laterally extending arm 44 thereon, sliding in a groove 45 in one of the securing posts of the frame.

When the pointer 16 reaches the zero point, a suitable switch is adapted to be tripped for the purpose of closing the circuit through any signaling mechanism, as, for instance, a light or a bell, or this switch may be operated to close the circuit through any desired mechanism. This switch, as noted, comprises a pair of spaced-apart contacts 46 and 47, mounted on an insulating bridge 48 and connected, respectively, to binding-posts 49 and 50, to which the conductors of the mechanism to be controlled are connected. The contacts are adapted to be bridged by a contact member 51 mounted upon an insulating arm 52 secured to the outer end of a tripping arm 53. This tripping arm is arcuate in form, as shown, and is pivoted at 54 upon the upper side of the plate 11. The arm is held against the tension of a coiled spring 55, one end of which is connected to the arm and the other to the plate 8 in non-tripping position by a cam member 56 mounted upon the shaft 12 and adapted to rotate with the pointer 16. This cam member 56 is provided with a recess or slot 57, which is rotated to a position to permit the pin 58 on the tripping arm to drop therein and permit the tripping arm to close the switch at the same moment that the pointer 16 reaches zero position. The tripping arm is provided with a projection 59 adapted to engage with a projecting arm 60 on the frame formed by the plates 33, and this frame is held against this projection by means of the coiled spring 61, one end of which is connected to the end of the dog 39 and the other end of which is connected to the tripping arm. In order that the pointer 16 will move back to the position from which it started, a coiled spring 62 is provided. This spring surrounds the shaft 12 and has one end connected to the plate 8 and the other end connected to the underside of the cam member 56, so that while the shaft is being rotated to move the pointer in a counter-clockwise direction the spring 62 will be wound to provide motive force to rotate the shaft in an opposite direction when the shaft is disconnected from the motor. The setting gear 18 is provided on its under face with a stop 63, which is adapted to be engaged by an upwardly projecting stop 64 on the gear 30, so that when the shaft is rotated under the influence of the spring 62 it will come to a stop at the proper position indicated. The trip arm 53 is re-set from

the exterior of the casing by means of the push-button 64^a on the end of a vertically movable rod 65. This rod is secured in the casing in the same manner as the shaft 23 and is provided with a collar 66 adapted to be engaged by one arm 67 of a bell crank lever pivoted at 68 to the under side of the plate 11. The opposite arm 69 of this bell crank lever bears against a laterally extending pin 70 secured to the pivot post 54 of the arm 53, this pivot post and arm being adapted to rock together. It is, therefore, apparent that when the button 64 is depressed, through the medium of the bell crank lever, the arm is rocked to disengage the pin 58 from the cam slot 57, at the same time moving the contact member 51 from between the contact blades 46 and 47 to open the switch. When the pin 58 has been disengaged from the slot 57 the cam 56 will rotate in an opposite direction from that in which it has been driven by the motor, until the stop 64 on the gear 30 engages the stop 63 on the setting gear 18, bringing the cam to rest at its designated point.

Mounted on the insulating bridge 48 is a pair of binding-posts 71, to which the leading-in wires or cables 72 are brought. These binding-posts are connected with the terminals of the driving motor 9 for the purpose of supplying power thereto. The leading-in wires 72 as well as the wires connected to the binding-posts 49 and 50 are brought in through an opening 73 in the casing, which opening is adapted to receive the end of the conduit through which the wires pass, and is thereby sealed against the entrance of the dust, and the like. The conductors 72 are adapted to be connected with an alternating-current circuit or any suitable source of power.

The motor for driving the apparatus is of a particular type and has strong starting and strong synchronizing characteristics, which, when connected with an alternating-current circuit, will run with extreme accuracy and with the minimum of attention. In general, the motor consists of a laminated field magnet 74 provided with a coil 75 and having its pole-pieces provided with shading coils 76 and 77 and with circular polar faces 78, 79, 80 and 81 and with straight faces 82 and 83 separated by substantially small or narrow air gaps. Within the rotary magnetic field formed by the pole-pieces and shading coils is an unwound rotor which is substantially non-polar geometrically and magnetically polar, and preferably is made of a circular disc 84 of hardened steel fast on a shaft 85. This rotor is provided with two pins or bars 86 and 87, preferably of hardened steel, which are located substantially diametrically opposite and extend in a direction substantially parallel

with the axis of the rotor, projecting into a portion of the magnetic field which is outside of the zone in which the disc 84 rotates. The shaft 85 is preferably mounted vertically to reduce wear on the bearings, and the relation between the rotor and the field is such that it is magnetically supported, so that when running it floats without appreciable end thrust. Motion from this shaft 85 is transmitted through a worm thread to a gear 88 and thence by a similar reduction gearing to the shaft 89 driving the pinion 10. This gearing is enclosed in a nearly airtight case 90, which contains an ample amount of lubricating oil so that the wear of the parts is reduced to a minimum and the attention required by the motor is practically nil. A cap 91 is placed over the disc, so that all of the parts are permanently enclosed.

In use, the motor runs continuously at a constant speed. To set the device so that the switch will be operated after the lapse of a predetermined time, for instance twenty minutes, the operator presses inwardly on the thumbpiece 24 to release this thumbpiece for rotation, and then rotate the thumbpiece to set the stop 63 at the desired point, this point being indicated by the pointer 15, the pointer 15 being set to point to the figure 20 on the dial. The operator then presses down on the push button 64^a. This pressing down on the button 64^a moves the pin 58 out of the notch 57, and permits the cam or disc 56 to fly around under the influence of the coiled torsion spring 62 until the stop member 64 comes up against the stop member 63.

The mechanism is now set and ready to start. To start the time-controlled movement of pointer 16, the starting button on the upper end at the vertically movable catch 42 is pressed down, to release the latch member or dog 39 to permit the plates 33, which form the movable frame, to swing inwardly to bring the pinion 31 into mesh with the gear 30. This starts the time-controlled movement of the gear 30, the cam member 56 and the pointer 16. This time-controlled movement continues until the notch 57 comes around into a position to permit the pin 58 to drop therein under the action of the tension spring 55. When the pin 58 drops into the notch, the arm 53 swings about its pivot, and closes the switch circuit in the contact member 51. Also, as the tripping arm 53 moves about its pivot, the projection 59 engages the projecting arm 60 on the swinging frame 33, which carries the pinion 31, moving this pinion 31 out of mesh with the gear 30, and thus stopping the time-controlled movement of the gear 30, and of the pointer 16. The parts will remain in this condition, with the motor running, but disconnected from the pointer

16, until it is again desired to reset the pointer 16, and to start the time-controlled movement, which is accomplished by simply pressing on the button 64^a to set the hand 16 back, and then pressing the starting button to let the pinion 13 swing into engagement with the gear 30.

Having thus described my invention, what I claim as new and desire to secure by 10 Letters Patent is:—

1. In a device of the character described, the combination with a switch, of a tripping means for said switch operating when said tripping means reaches a predetermined 15 point, means for retracting said tripping means from said point, a stop for determining the distance from said point said tripping means is retracted, an electric motor having a rotating armature for driving said 20 tripping means, and means for disconnecting said armature from said tripping means.

2. The combination with a switch, of a tripping means for said switch operating when the tripping means reaches a predetermined point, means for retracting said tripping means from said point, an adjustable 25 stop for determining the distance from said point said tripping means is retracted, an electric motor having a rotating armature for driving said 30 tripping means, and means for disconnecting said armature from said tripping means.

3. The combination with a switch, of a tripping means for said switch operating 35 when it reaches a predetermined point, means for retracting the same from said point, a stop for determining the distance from said point said tripping means is retracted, an electric motor having a constantly 40 rotating armature for driving said tripping means, and means for automatically disconnecting said armature from said tripping means upon the tripping of said switch.

4. The combination with a switch, of a tripping means for said switch operating 45 when said tripping means reaches a predetermined point, means for retracting said tripping means from said point, a stop for determining the distance from said point 50 the tripping means is retracted, an electric motor having a constantly rotating armature for driving said tripping means, means for automatically disconnecting said armature from said tripping means when the switch 55 is tripped, manually-operated means for causing said retracting means to operate, and manually-operated means for causing said armature to be connected with said tripping means.

5. In a device of the character described, the combination with a rotatable shaft, of a tripping means operated when said shaft has made a predetermined movement of rotation, a motor having a rotating armature,

a movable member having a driving gear 65 for said shaft connected with said armature, and means for moving said member to disconnect said driving gear from the shaft.

6. In a device of the character described, the combination with a shaft, of a tripping 70 means operated by said shaft when the shaft has made a predetermined movement of rotation, a motor having a rotating armature, a movable member having a driving gear 75 for said shaft connected with said armature, and means for automatically moving said member to disconnect the driving gear when the tripping device is operated.

7. In a device of the character described, the combination with a movable switch member having a tendency to move to operate, a rotatable member holding said switch member against operation and having means which, when said rotatable member has reached a predetermined point, permits the 80 switch member to operate, a driving gear for said rotatable member, a motor having a rotating armature, and means for disconnecting said armature from said driving 85 gear when the switch member operates.

8. In a device of the character described, the combination with a switch, of a tripping device for operating said switch when said tripping device has been moved a predetermined distance, a motor having a rotating armature, means for connecting said motor with said tripping device for driving the same, and means operated by said tripping device for disconnecting the motor and holding 90 the motor disconnected.

9. A time-controlled mechanism comprising a synchronous motor, operable means which it is desired shall be operated after the lapse of a predetermined period of time, movable means for controlling the instant 105 of operation of said operable means, means whereby the rate of movement of said movable means in one direction is controlled by said time-controlled mechanism, and power means for returning said movable means 110 after its time-controlled movement.

10. A time-controlled mechanism comprising a synchronous motor, operable means which it is desired shall be operated after the lapse of a predetermined period of time, movable means for controlling the instant 115 of operation of said operable means, means whereby the rate of movement of said movable means in one direction is controlled by said time-controlled mechanism, power 120 means for returning said movable means after its time-controlled movement, and indicating means for indicating the adjustment of said movable means.

11. A time-controlled mechanism comprising a synchronous motor, operable means which it is desired shall be operated after the lapse of a predetermined period of time,

movable means for controlling the instant of operation of said operable means, means whereby the rate of movement of said movable means in one direction is controlled by said time-controlled mechanism, power means for returning said movable means after its time-controlled movement, and means for limiting said return movement to determine the duration of the time-controlled movement.

12. A time-controlled mechanism comprising a synchronous motor, operable means which it is desired shall be operated after the lapse of a predetermined period of time, movable means for controlling the instant of operation of said operable means, means whereby the rate of movement of said movable means in one direction is controlled by said time-controlled mechanism, power means for returning said movable means after its time-controlled movement, means for limiting said return movement to determine the duration of the time-controlled movement, and means for adjusting said limiting means.

13. A time-controlled mechanism comprising a synchronous motor, operable means which it is desired shall be operated after the lapse of a predetermined period of time, movable means for controlling the instant of operation of said operable means, means whereby the rate of movement of said movable means in one direction is controlled by said time-controlled mechanism, power means for returning said movable means after its time-controlled movement, movable means for limiting said return movement, to determine the duration of the time-controlled movement, and means for causing said limiting means to move in a definite path.

14. A time-controlled mechanism comprising a synchronous motor, operable means which it is desired shall be operated after the lapse of a predetermined period of time, movable means for controlling the instant of operation of said operable means, means whereby the rate of movement of said movable means in one direction is controlled by said time-controlled mechanism, power means for returning said movable means after its time-controlled movement, movable means for limiting said return movement to

determine the duration of the time-controlled movement, means for causing said limiting means to move in a definite path, manually operable means for adjusting said limiting means, and indicating means for indicating the adjusting of said adjusting means.

15. A time-controlled means, operable means which it is desired should be operated after the lapse of a predetermined period of time, movable means for controlling the instant of operation of said operable means, comprising a rotatable cam, means whereby the rate of movement of said movable means in one direction is controlled by said time-controlled mechanism, power means for returning said movable means after its time-controlled movement, and means for limiting said return movement to determine the duration of the time-controlled movement.

16. A time-controlled means, operable means which it is desired should be operated after the lapse of a predetermined period of time, movable means for controlling the instant of operation of said operable means, comprising a rotatable cam and a spring arm controlled by said cam, means whereby the rate of movement of said movable means in one direction is controlled by said time-controlled mechanism, power means for returning said movable means after its time-controlled movement, and means for limiting said return movement to determine the duration of the time-controlled movement.

17. A time-controlled means, operable means which it is desired should be operated after the lapse of a predetermined period of time, movable means for controlling the instant of operation of said operable means, transmission means between said time-controlled means and said movable means, whereby the rate of movement of said movable means in one direction is controlled by said time-controlled means, power means for returning said movable means after its time-controlled movement, means for limiting said return movement to determine the duration of said time-controlled movement, and means for disconnecting said transmission means comprising a shiftable gear.

In witness whereof, I have hereunto subscribed my name.

CHARLES M. CROOK.
